TROUSER REMOVER

Otto Boruvka, New York, N. Y.

Application August 15, 1956, Serial No. 604,106

4 Claims. (Cl. 223—111)

2

Fig. 5 is a bottom plan view of the device viewed in an inverted position with bottom cover plate removed.

Fig. 6 is a sectional view similar to Fig. 4 illustrating a modification of the invention.

5 Fig. 7 is an enlarged plan sectional view of a portion of the modified form of the device taken on lines 7—7 of Fig. 6.

Fig. 8 is a perspective view of portions of the shank and finger with rubber friction hoods or caps mounted thereon.

10 Fig. 9 is a perspective view of a pedal used in the device with a friction cover or hood mounted thereon.

Fig. 10 is a sectional view taken on lines 10—10 of Fig. 9.

Fig. 11 is a perspective view of a pair of pedal shafts 15 and an associated rod actuating pin employed in the modified form of the device.

The device as shown in Figs. 1—5 has a hollow box-like body formed by a generally rectangular frame 20 having parallel sides 21 with forwardly converging wall portions

20 22. A flat bottom plate 23 and top plate 24 serve to complete the box structure. The plates are shaped to conform with the outline of the frame 20. Plate 23 is secured to frame 20 by screws 19 threaded in holes 18 in the frame. On plate 24 is secured a channel member 26.

25 A bar 27 having an upturned finger portion 28 is slideable in channel member 26. Screws or bolts 29 serve to secure the member 26 to plate 24. Screws 30 secure plate 24 to frame 20. The frame 20 and plates 23, 24 may be made of wood, metal or plastic material. At the front

30 32 of the frame 20 is mounted an upstanding finger member 32. The inner or rear side 33 of this shank is shaped or curved to conform with the corresponding forward side 34 of finger 28. Finger 32 is held to the forward end of the frame by a screw 35 on which is threaded a nut 36.

35 In plate 24 is a slot 37. A rod or shaft 38, as best shown in Fig. 4, extends from bar 27 through this slot and supports a block 40 for longitudinal movement in the box. Rod 38 terminates in a head 41.

A pair of flat rectangular plates 43, 44 are disposed 40 outside the box at an angle to plates 23 and 24. These plates are secured to a shaft 45 which extends transversely through the box. Clamps 46 serve to secure the plates 43, 44 to the shaft on opposite sides of the box. Screws 47 secure the clamps to the plates. On shaft 45 is mounted

45 a short rod 49 which bears against the inclined edge 50 of block 40. This rod is anchored in shaft 45 and pivots therewith. A pair of springs 51, 52, as best shown in Figs. 4 and 5, are secured at one end to hooks 54. Hooks 54 are mounted in the parallel sides 21 of the box frame

50 20. The other ends of the springs 51, 52 are attached to hooks 55 mounted on the sides of block 40. The springs 51, 52 are biased so that the plates 43, 44 are held in the angular position mentioned above and shown in the drawing, and rod 49 bears on edge 50 of the block 40. Plates

55 43, 44 serve as pedals which when pressed downwardly as indicated by arrow 60 cause the rod 49 to move the block forwardly until finger 28 touches finger 32. When the pedals are released, springs 51, 52 return the block 40 to its normal rearward position with bar 27 fully retracted within channel member 26.

A tab 58 is attached to the rear side 59 of the box by a screw 61. This tab has an aperture 63 whereby the box may be hung on a suitable hook or bracket when not in use. The tab fits in a recess 64 in rear wall 59 of frame

65 20. Plate 23 abuts the tab 58.

In Fig. 6 is shown a modification of the invention in which a corrugated rubber hood or cap 65 is mounted on finger 32. A similar hood 66 is mounted on finger 28. These hoods have corrugated surfaces 33', 34' arranged

70 to contact each other when the finger 28 is advanced by operation of the pedals. Another pair of hoods 67 as best shown in Figs. 9 and 10 are mounted over the pedal

This invention concerns a trousers removing device. There are many persons suffering from lumbago, backaches and various afflictions of the spine and sacroiliac regions so that it is difficult or impossible for these persons to bend from an erect or sitting position. When these persons have to remove trousers or slacks it generally requires the assistance of another person. The conditions accompanying obesity lead to a similar situation where bending to any considerable extent from an erect position is not possible. For such persons the need has long existed for a practical trousers removing device usable by both men and women.

It is therefore a principal object of the invention to provide a trousers remover operable by a person wearing the trousers and requiring no assistance from another person.

It is a further object to provide a trousers remover or trousers jack provided with pedals and finger means for gripping the bottom of a trousers leg so that the trousers may be drawn off from the body while one or both pedals are depressed.

According to the invention there is provided a box of suitable shape having an upstanding finger fastened to the front thereof. The box has a top with a slot in the middle over which is a channel member in which fits a slideable bar having an upstanding finger portion shaped to conform with the finger on the front of the box. The slideable bar has a depending shaft attached to a block in the box. A pair of pedals are pivotably mounted on a shaft which extends transversely into the box. The shaft carries a radially extending pin arranged to move the block and slideable bar when a pedal is depressed. Springs or rubber bands return the block to its original position when the pedal is released.

When a pedal is depressed while the bottom of a trousers leg is disposed between the upstanding fingers, the bottom of the trousers leg is securely gripped and can be removed from the leg of the wearer while the pedal is depressed. In a modification of the invention, means are provided to make the pedals independently movable, also friction pads, hoods or covers are provided for the upstanding fingers, for the pedals, and for the bottom of the box to increase efficiency of operation thereof. The device is usable by men and women generally as a valet accessory and may be used by able-bodied as well as disabled persons.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a device embodying the invention.

Fig. 2 is a side elevational view of the device.

Fig. 3 is a top plan view of the device.

Fig. 4 is a vertical sectional view taken on lines 4—4 of Fig. 3.

plates 43, 44. These hoods 67 have corrugated surfaces 67' arranged to provide a frictional surface on the pedals. Attached to plate 23 is a pad 69 having a corrugated surface 70 which provides a frictional surface 70 underneath the device.

The axial support for the pedals is modified as shown in Figs. 6, 7 and 11 so that the pedals are independently movable. The shaft 45' has a pair of hollow tubular sleeve-like ends 45" in which fit the stub shafts 72. Pedals 43, 44 are secured to these stub shafts. Pins 73 extend through arcuate slots S in shaft 45'. These pins are attached to shafts 72. The arcuate slots S in shaft 45' permit limited angular movement of the shaft 45' by one pin 73 without disturbing the position of the other pin. The pins 73 have hooked or looped ends 74 to which are secured the springs 81, 82. The other ends of the springs are secured to hooks 75 anchored in the rear wall 59.

In Figs. 6 and 7 the springs 51, 52 are replaced by rubber bands 83 attached to hooks 84 on block 40, and to hooks 85 on the rear wall 59. A pair of washers 86 are mounted on shafts 72 between the pedals and the side walls 21 of the box. Similar washers are mounted on shaft 45 as shown in Fig. 1. In operation either pedal 43 or 44 may pivot forwardly as indicated by arrow 60 to cause the rod 49 to advance block 40. The corresponding shaft 72 of the pedal which is pivoted moves angularly against tension in the attached spring 81 or 82. The other pedal remains undisturbed since the sleeve end 45" of shaft 45' with its slot S moves angularly with respect to the undisturbed pin 73.

In Figs. 9 and 10 is shown a modified form of attachment for the pedal to its shaft. The clamp 46 is omitted and the curved end 46' of the pedal extends around and is press fitted to the shaft 72.

In operation of either form of the devices shown in Figs. 1 or 6, the user stands in front of the box and inserts the bottom of one trousers or pants leg between the two open fingers 28, 32. He then steps with the foot of his free leg on the nearest pedal to secure the bottom of the leg of the garment tightly between the fingers. By bending the first leg and raising it upward while lowering the trousers from the waist, the user can remove his first leg and step out of the trousers leg being held between the juxtaposed fingers. The operation may then be repeated with the other trousers leg while the user steps on the other pedal with his free foot. The trousers, pants or slacks are thus removed without requiring any bending of the back or undue strain on the back or abdominal muscles.

The device may be used by both men and women and is a convenient valet accessory for well persons as well as persons who are partially disabled.

While I have illustrated and described the preferred embodiments of my invention, it is to be understood that I do not limit myself to the precise constructions herein disclosed and that various changes and modifications may be made within the scope of the invention as defined in the appended claims.

Having thus described my invention, what I claim as new, and desire to secure by United States Letters Patent is:

1. A trousers remover comprising in combination: a hollow box, said box having an upper cover plate with a slot therein, a channel member attached to said plate, a bar slidably disposed in said channel member and carrying a depending rod extending through the slot in said plate, a block supported on said rod and movable longitudinally in said box, said block having an inclined edge, a shaft pivotably disposed in said box, a short rod radially secured to said shaft and having its free end arranged to

contact the inclined edge of said block, a spring member attached between said block and a wall of said box to retract said block, a pair of pedals secured to said shaft, said pedals being disposed at opposite sides of the box, a first upstanding finger fixed to a forward portion of said box, and a second upstanding finger formed on said bar, said fingers having curved portions arranged to interfit with each other when said second finger is advanced, said second finger being advanced when one of said pedals is depressed, whereby a lower portion of a trousers leg may be gripped between said fingers when one of the pedals is depressed and whereby said trousers leg is released when said one pedal is released.

2. A trousers remover comprising in combination: a hollow box, said box having an upper cover plate, with a slot therein, a channel member attached to said plate, a bar slidably disposed in said channel member and carrying a depending rod extending through the slot in said plate, a block supported on said rod and movable longitudinally in said box, a shaft pivotably disposed in said box, a short rod radially secured to said shaft and having its free end arranged to contact said block, a spring member attached between said block and said box to retract said block, a pair of pedals secured to said shaft, said pedals being disposed at opposite sides of the box, a first upstanding finger fixed to a forward portion of said box, and a second upstanding finger formed on said bar, said fingers having portions shaped to interfit with each other when said second finger is advanced, said second finger being advanced when one of said pedals is depressed, whereby a lower portion of a trousers leg may be gripped between said fingers when one of the pedals is depressed, and whereby said trousers leg is released when said one pedal is released.

3. A trousers remover comprising in combination: a hollow box, said box having removable upper and lower plates, the upper plate having a slot therein, a channel member attached to said upper plate, a bar slidably disposed in said channel member, a rod depending from said bar and extending through the slot in said upper plate, a block supported on said rod and movable longitudinally in said box, a shaft pivotably disposed in said box, a short rod radially secured to said shaft and having its free end arranged to contact said block, a spring member attached between said block and said box to retract said block, a pair of pedals operatively secured to said shaft, said pedals being disposed at opposite sides of the box, a first upstanding finger fixed to a forward portion of said box, and a second upstanding finger formed on said bar and normally spaced from the first finger, said fingers being arranged to interfit with each other when said second finger is advanced by pivoting one of said pedals forwardly, whereby a lower portion of a trousers leg may be gripped between said fingers when one of the pedals is depressed, and whereby said trousers leg is released when said one pedal is released.

4. A trousers removing device, comprising a hollow box, a pair of pedals pivotally attached to said box, one pedal being on each side of the box, a first finger fixed to a forward portion of said box, a second finger movably mounted on said box, inwardly of the first finger, a shaft journaled in the box and mounting said pedals and second finger, said fingers having sides disposed to contact each other when at least one of said pedals is depressed.
